(57) **CLAIM**

The ornamental design for a gaming machine, as shown and described.

DESCRIPTION

FIG. 1 is a left front perspective view of a gaming machine showing our new design;

FIG. 2 is a right front perspective view thereof;

FIG. 3 is a front view thereof;

FIG. 4 is a top view thereof; and,

FIG. 5 is a cross-sectional view taken along 5-5 of FIG. 4. The broken line showing of the remainder of the gaming machine illustrates environmental structure and forms no part of the claimed design. The oblique line shading depicts a transparent, translucent, highly polished or reflective surface.
